By their Attorney PAUL HUSAK

Oscar Geier

UNITED STATES PATENT OFFICE.

WASYL WOZNY AND PAUL HUSAK, OF BOUND BROOK, NEW JERSEY.

COMBINATION PENHOLDER AND BLOTTER.

1,243,911.

Specification of Letters Patent.

Patented Oct. 23, 1917.

Application filed July 6, 1917. Serial No. 179,017.

To all whom it may concern:

Be it known that we, **WASYL WOZNY**, a subject of the Emperor of Austria, resident of Boundbrook, county of Somerset, and **PAUL HUSAK**, a subject of the Emperor of Austria, resident of Boundbrook, county of Somerset, and State of New Jersey, have invented certain new and useful Improvements in Combination Penholders and Blotters, of which the following is a specification.

This invention relates to improvements in combined pen holders and blotters, and has as its special object the provision of means whereby a blotting surface may be intimately combined with the penholder, thereby forming a convenient article for office and home use.

A further object is to provide a blotter so constructed that the outer layer may be readily removed, thereby presenting a fresh face at such times as may be desired.

These and other like objects are attained by the novel construction and combination of parts hereafter described and shown in the accompanying drawing, forming a material part of this disclosure, and in which—

Figure 1 is a side elevational view of an implement made in accordance with the invention.

Fig. 2 is a top plan view of the same, and

Fig. 3 is an enlarged transverse section taken on line 3—3 of Fig. 1.

In the drawing, the numeral 10 designates the pen holder to which may be attached the pen nib 11, in the ordinary manner, the op-

posite end 12 of the pen holder containing longitudinally disposed recesses 14 extending in from the end, and pivoted by the pins 15, on each side thereof, are wires 16, extending out into broadened loops 18, around which is wound several convolutions of blotting paper 20 or like material, presenting in effect a pad which may be conveniently used in blotting moist ink in an exceptionally convenient manner, dispensing with the necessity of using a separate piece of blotting paper or an implement adapted particularly for that purpose, while the resiliency of the wire loops 18 is such as to permit the pad of blotting paper to assume any desired position relative to the sheet to be blotted.

Having described the construction and operation of our invention, what we claim as new, and desire to secure by Letters Patent, is—

1. In a writing implement, the combination with a pen holder, of a spring loop secured at the end thereof, and a strip of absorbent material coiled plurally about said loop.

2. In a writing implement, the combination with a penholder, of a looped resilient wire pivotally engaged at one end thereof, said looped wire having an extending loop beyond said penholder, and a strip of blotting material wound about said loop forming a pad.

In testimony whereof we have affixed our signatures.

WASYL WOZNY.
PAUL HUSAK.
